PROCESS FOR THE SULPHONATION OF
ALPHA NITRO NAPHTHALENEJohn M. Tinker, Penns Grove, N. J., assignor to
E. I. du Pont de Nemours & Company, Wilming-
ton, Del., a corporation of DelawareNo Drawing. Application July 26, 1937,
Serial No. 155,780

7 Claims. (Cl. 260—505)

The present invention relates to a process for the production of nitro-naphthalene sulphonic acids. More particularly it relates to a process for the production of nitro-naphthalene sulphonic acids from nitro-naphthalene. Still more particularly it relates to an improved process for the production of 1-nitro-naphthalene-5-sulphonic acid from 1-nitro-naphthalene.

10 Nitro-naphthalene sulphonic acids have been produced in the prior art by the sulphonation of 1-nitro-naphthalene. Various sulphonating agents such as oleum, oleum plus sodium chloride, and chloro-sulphonic acid were employed in this prior art process but it was found that many unsatisfactory effects resulted from their use. Thus, in the use of oleum and in the use of chloro-sulphonic acid the reaction was found to be too vigorous, thereby resulting in charring, discoloration, and in very poor yields. Although the use 20 of oleum plus sodium chloride gave a satisfactory yield there were still present other difficulties such as the evolution of hydrogen chloride in large quantities which caused serious corrosion and also, the presence of a toxic condition which 25 condition proved to be dangerous to the workers.

It is an object of the present invention to manufacture nitro-naphthalene sulphonic acids by a simple and efficient process. A further object is to manufacture nitro-naphthalene sulphonic acid 30 from nitro-naphthalene in the presence of a sulphonating agent. A still further object is to manufacture 1-nitro-naphthalene-5-sulphonic acid from 1-nitro-naphthalene. A still further object is to overcome the difficulties which were encountered in the prior art processes of making nitro-naphthalene sulphonic acid. Additional objects 35 will become apparent from a consideration of the following description and claims.

These objects are attained according to the 40 herein described invention which broadly comprises sulphonating a nitro-naphthalene in the presence of a strong sulphonating agent and salt of a non-volatile acid. In a more restricted sense this invention comprises sulphonating nitro-naphthalene, in the presence of a strong sulphonating agent and a salt of sulphuric acid. The preferred embodiment of this invention comprises sulphonating 1-nitro-naphthalene in the presence 45 of oleum and a salt of sulphuric acid. Exceptionally good results have been obtained by the use of sodium sulphate and for this reason, it is the preferred salt.

This invention may be more readily understood 50 by a consideration of the following example.

Example

Heat a mixture of one thousand grams of 24% oleum, (76% H_2SO_4 + 24% free SO_3), 410 g. of anhydrous sodium sulphate and 500 g. of 100% sulphuric acid to 40–50° C. and add during one hour, 500 g. of 1-nitro naphthalene. Heat the mass at 50–55° C. for 18 hours. Heat another hour at 85° C. Pour onto 10 liters of water, neutralize with lime and filter. On evaporation of the 10 water the nitro-naphthalene calcium sulphonates are obtained in a quantitative yield. On reduction of the calcium or sodium salts of the mixed nitro-naphthalene-sulphonic acids with iron and acid, mixed naphthylamine sulphonic acids are obtained from which 70% of the theoretical yield of 15 Laurent's acid (1-naphthylamine-5-sulphonic acid) can be isolated by known methods.

It is seen from an examination of the above 20 example that Laurent's acid may be obtained by reducing with iron and sulphuric acid the nitro-naphthalene sulphonic acid followed by extraction of the Laurent's acid from the iron sludge with sodium carbonate solution.

It is to be understood that the aforementioned 25 example is representative only of the method of the practice of the invention. This method may be subjected to variation and modification. For instance in place of sodium sulphate, referred to in the preceding example, or in admixture therewith it is to be understood that salts of other non-volatile acids or other salts of sulphuric acid may 30 be used. A few representative examples of materials falling within this category are sodium bisulphate, ammonia salts of non-volatile acids, 35 alkali metal and alkaline earth metal salts of non-volatile acids such as sulphuric, boric, phosphoric, naphthalene sulphonic, and the like. The alkali and alkaline earth sulphates and bisulphates generally as well as the sulphates and bisulphates of related metals have been found to give excellent results. As previously mentioned, these salts may be used alone or in admixture with one another and when used in admixture with one another the proportions may vary widely 40 without departing from the scope of this invention. However, it is to be understood that sodium sulphate is the preferred salt for use herein.

The proportion of the salt to the sulphonating 50 agent and the proportion of the sulphonating agent to the nitro-naphthalene may vary widely without departing from the scope of this invention. However, the preferred results have been obtained when the molar ratio of the salt to sulphur tri-oxide and of the sulphur tri-oxide to 55

nitro-naphthalene has been within the range of 1 to 3 moles of salt to 1 mole of sulphur tri-oxide and 1 to 3 moles of sulphur tri-oxide to 1 mole of nitro naphthalene.

5 It is preferred to use the aforementioned salts in the anhydrous form because an increased amount of oleum is required when the wet salt is used. However, it is to be understood that the salt in the hydrated form may be used without 10 departing from the scope of this invention.

The term "oleum" as used in the disclosure as well as the appendant claims means sulphuric acid containing free sulphur tri-oxide.

By means of the present invention an entirely 15 new class of salts are used in the production of nitro-naphthalene sulphonic acid. Due to the presence of said salts in the sulphonation of nitro-naphthalene it is possible to produce nitro-naphthalene sulphonic acid by a process which is 20 superior and more economical than any heretofore known. Further, the defects of vigorous reactions, charring, discoloration, poor yield, formation of hydrogen chloride, toxic condition, etc. are overcome by my herein disclosed invention.

25 As many apparently widely different embodiments of this invention may be made without departing from the scope and spirit thereof, it is to be understood that the invention is not limited to the specific embodiments thereof except as defined in the appended claims.

Having disclosed the present invention the following is claimed as new and useful:

1. A process which comprises sulphonating a 30 nitro-naphthalene in the presence of a mixture of a strong sulphonating agent and a salt of sulphuric acid selected from the class consisting of alkali metal, alkaline earth metal, and ammonium salts.

2. A process which comprises sulphonating a nitro-naphthalene in the presence of a mixture of oleum and a salt of sulphuric acid selected from the class consisting of alkali metal, alkaline earth metal, and ammonium salts.

5 3. A process which comprises sulphonating a nitro-naphthalene in the presence of a mixture of oleum and sodium sulphate.

4. A process which comprises sulphonating 1-nitro-naphthalene in the presence of a mixture 10 of oleum and sodium sulphate.

5. A process which comprises sulphonating a nitro-naphthalene in the presence of a mixture of a strong sulphonating agent and salt of a non-volatile acid selected from the class consisting 15 of alkali metal, alkaline earth metal, and ammonium salts of sulphuric, boric, phosphoric and sulphonic acids.

6. A process which comprises sulphonating nitro-naphthalene in the presence of a mixture of 20 oleum and sodium sulphate, in the absence of any volatile acid, the molar ratio of the salt to sulphur tri-oxide and of the sulphur tri-oxide to nitro-naphthalene being within the range of 1 to 3 moles of salt to 1 mole of sulphur tri-oxide and 25 1 to 3 moles of sulphur tri-oxide to 1 mole of nitro-naphthalene.

7. A process which comprises sulphonating 1-nitro-naphthalene in the presence of a mixture of oleum and sodium sulphate, in the absence of a 30 volatile acid, the molar ratio of the salt to sulphur tri-oxide and of the sulphur tri-oxide to nitro-naphthalene being within the range of 1 to 3 moles of salt to 1 mole of sulphur tri-oxide and 35 1 to 3 moles of sulphur tri-oxide to 1 mole of nitro-naphthalene.

JOHN M. TINKER.

CERTIFICATE OF CORRECTION.

Patent No. 2,143,963.

January 17, 1939.

JOHN M. TINKER.

It is hereby certified that error appears in the printed specification of the above numbered patent requiring correction as follows: Page 1, second column, line 6, for "40-50° C." read 40-45° C.; and that the said Letters Patent should be read with this correction therein that the same may conform to the record of the case in the Patent Office.

Signed and sealed this 21st day of February, A. D. 1939.

Henry Van Arsdale.

(Seal)

Acting Commissioner of Patents.
